(57) **CLAIM**

We claim the ornamental design for a rake handle, as shown and described.

DESCRIPTION

FIG. 1 is a front perspective view of an embodiment of the claimed design;

FIG. 2 is a rear perspective view of the claimed design of FIG. 1;

FIG. 3 is a front elevation view of the claimed design of FIG. 1;

FIG. 4 is a rear elevation view of the claimed design of FIG. 1;

FIG. 5 is a right side view of the claimed design of FIG. 1;

FIG. 6 is a left side view of the claimed design of FIG. 1; and,

FIG. 7 is a top view of the claimed design of FIG. 1.

The ornamental design which is claimed is shown in solid lines in the drawings.

The broken lines represent environment and form no part of the claimed design.

1 Claim, 6 Drawing Sheets
